Fig. 9. A. 16

Technical drawing of a spiral spring assembly. The drawing shows a central vertical axis with a flared top section. A spiral spring is wound around this axis. Several components are labeled with numbers: 20 at the top, 13 on the left, 26 on the right, 21 below the spring, 19 near the bottom, and 20 at the very bottom. To the right of the spring, the text 'FIG. 6.' is written in a large, cursive font. Below the drawing, the text 'R.C.' is written in a large, cursive font.

UNITED STATES PATENT OFFICE.

ALEXANDER C. MORRIS, OF CLARKSTON, WASHINGTON, ASSIGNOR OF ONE-HALF TO
ALFRED P. HOLLINGSWORTH, OF CLARKSTON, WASHINGTON.

COMBINATION FENCE-POST.

1,263,098.

Specification of Letters Patent. Patented Apr. 16, 1918.

Application filed November 2, 1916. Serial No. 129,164.

To all whom it may concern:

Be it known that I, ALEXANDER C. MORRIS, a citizen of the United States, residing at Clarkston, in the county of Asotin and State 5 of Washington, have invented certain new and useful Improvements in Combination Fence-Posts, of which the following is a specification.

This invention relates to improvements in 10 posts and similar structures, more particularly to fence posts and the like, and has for one of its objects to provide a device of this character combining all of the advantages of a wooden post and a reinforced concrete 15 base portion, thus securing the convenience of the wood post with the durability of the concrete base.

Another object of the invention is to provide a post formed with a concrete base, a 20 wood or like upper portion, and suitable reinforcing and supporting elements firmly connecting the wood portion to the concrete base portion.

Other and incidental objects will appear 25 as the description proceeds, and in the drawings wherein I have illustrated the preferred embodiment of the invention and wherein similar reference characters designate corresponding parts throughout the several views:

30 Figure 1 is a perspective view of one of the improved posts,

Fig. 2 is a perspective view of the reinforcing elements of the improved device without the wood and concrete portions,

35 Fig. 3 is an enlarged vertical section,

Fig. 4 is a transverse section on the line 4—4 of Fig. 3,

Fig. 5 is an enlarged detail of a portion 40 of the reinforcing element,

Fig. 6 is an enlarged detail view similar to Fig. 5, illustrating a modification in the construction.

The improved device may be employed for 45 posts of various forms, such as fence posts and the like, and may likewise be employed for telephone, telegraph, electric light posts and supports for trolley wires, and for similar purposes, and it is not desired therefore to limit the invention in this respect, but for 50 the purpose of illustration, the improved device is shown arranged as an ordinary fence post and comprises an upper wood portion 10 and a lower concrete portion or base 11 upon which the lower end of the wood portion 10 rests. The concrete base is of greater

diameter than the wood portion as shown, and is adapted to be embedded in the ground indicated at 12.

The portions 10—11 are united by suitable anchoring devices illustrated in detached form in Fig. 2, and comprising a plurality of stay members of relatively heavy wire bearing over the upper end of the post and engaging its sides and secured at suitable intervals by staples 13 or like devices. 60 The upper end of the post is preferably provided with a cap indicated at 14, the cap being somewhat larger than the portion 10 of the post so that it overlaps the sides of the same and forms a shield or guard to protect 70 the post from moisture. The cap is provided with notches 15 to receive the stay members as shown in Fig. 1. Any required number of the stays may be employed but generally four will be used as shown, and when the 75 wood portion 10 of the post is of square form, one of the stays will bear against each side of the post. One opposite pair of the stays, designated by the reference character 16, are continued below the lower line of the 80 portion 10 of the post and embedded in the concrete portion 11 and brought together within the bottom of the concrete base and coupled as shown at 17.

Bearing around the opposite sides of the 85 portion 10 of the post near its lower end, are horizontal stay members 18—19 which pass beneath the said members 16 and are secured by a pair of the staples 13 one of which is shown in Fig. 1. The other pair of 90 vertical stay members are designated by the character 20 and where the latter are joined by the band members 18—19, the three portions, namely the vertical stay members 20 and the horizontal stay members 18—19, are 95 twisted, as shown at 21 and continued in twisted relation downwardly through the concrete and brought together near the bottom of the concrete with their terminals interlocked as shown at 22. By this means, 100 the vertical stay members are firmly anchored in the concrete and the post effectually supported in position upon the concrete base and prevented from either vertical or lateral displacement. Inserted in the lower 105 end of the wood portion 10 of the post is a relatively heavy rod 23 which extends below the lower end of the post and for a considerable distance into the concrete base and is formed with a laterally enlarged head 24. 110

as shown in Fig. 3. A plurality of wire stays 25 connect the vertical stay members within the concrete and likewise engage around the rod 23. In constructing the improved post, the stay members are secured to the wood portion 10 of the post, the rod 23 is inserted therein and the portions of the stay devices which depend below the wood portion 10 of the post are inserted in 10 a suitable mold and the concrete in plastic condition is poured into the mold and around the depending portions of the stay devices, so that when the concrete has "set," a very rigid and substantial post structure 15 is produced as will be obvious. Under certain condition, the stay members 18—19 may be dispensed with and the terminals of the twisted portions 21 looped around the vertical members 20, as shown at 26 in Fig. 6. 20 The cap 14 may be of concrete, metal, wood, or other material.

Having thus described my invention, what I claim as new is:

1. A fence post comprising a plastic base, 25 an upright resting on the base, a cap fitting the top of the upright and having its marginal edge projecting laterally beyond the side walls of the upright and provided with seating notches, oppositely disposed substantially inverted U-shaped longitudinal stay members having their upper ends extending across the top of the cap and intersecting at the center thereof, and their side portions seated in the notches in the cap and thence 30 extended downwardly in contact with the adjacent outer faces of the standard with their lower ends embedded in the plastic base, and fastening devices securing the stay members to the outer faces of the standard.
2. A fence post comprising a plastic base, 35 a standard resting on the base, oppositely disposed inverted U-shaped longitudinal stay members passing over the top of the standard and down the sides thereof and in contact with the exterior faces of the standard and having their lower ends united and embedded in the plastic base, a transverse stay member encircling the standard above

the plastic base and comprising substantially U-shaped portions, the ends of which 50 extend around the adjacent side portions of the longitudinal stay members and are intertwined with each other and with the side portions of said longitudinal stay members.

3. A fence post comprising a plastic base, 55 a standard resting on the base, an anchor rod embedded in the base and extending upwardly within the standard, intersecting inverted U-shaped longitudinal stay members passing over the top of the standard and 60 having their side portions disposed in contact with and secured to the adjacent faces of the standard and thence extended within the plastic base, a transverse stay member encircling the standard above the base and 65 comprising U-shaped members having their ends intertwined with each other and with the side portions of the adjacent longitudinal stay members, and superposed transversely disposed stay bars fitting around the 70 anchor bolt, the ends of one of the tie bars fitting around the intertwined portions of the transverse stay members, and the ends of the other tie bar fitting around the longitudinal stay members.

4. A fence post comprising a plastic base, 75 a wooden standard resting on the base, oppositely disposed inverted U-shaped longitudinal stay members passing over and intersecting at the top of the standard and thence 80 extended downwardly in contact with the outer side faces of the standard with their lower ends united and embedded in the plastic base, a transverse stay member encircling the standard in spaced relation to the plastic 85 base and having its terminal portions intersecting the adjacent longitudinal stay members and intertwined therewith, and fastening devices spanning the point of intersection of the terminals of the transverse stay 90 members with the longitudinal stay members and engaging the standard for preventing accidental displacement of both the longitudinal and transverse stay members.

In testimony whereof I affix my signature. 95
ALEXANDER C. MORRIS. [L. s.]
